UNITED STATES PATENT OFFICE.

EMMA V. LAKE, OF PHILADELPHIA, PENNSYLVANIA.

GARMENT-HOOK.

SPECIFICATION forming part of Letters Patent No. 752,457, dated February 16, 1904.

Application filed September 11, 1903. Serial No. 172,723. (No model.)

To all whom it may concern:

Be it known that I, EMMA V. LAKE, a citizen of the United States, residing in the city and county of Philadelphia, State of Pennsylvania, have invented new and useful Improvements in Garment-Hooks, of which the following is a specification.

My invention consists of a hook for a garment or other purpose in which provision is made for securing the opposite ends thereof to the place of service, so that rising, slipping, or shifting of the hook, especially at the bill end, is prevented, the other end being adapted to be secured as usual.

15 It also consists in providing the bill end of the hook with an attaching device, so located as to prevent the eye member which engages the hook from contacting with and cutting the stitches on said device.

20 It also consists of details of construction, as will be hereinafter described.

Figure 1 represents a plan view of a hook embodying my invention. Fig. 2 represents a side elevation thereof. Fig. 3 represents a 25 longitudinal section on line $\alpha\alpha$, Fig. 1. Fig. 4 represents a perspective view thereof.

Similar letters of reference indicate corresponding parts in the figures.

Referring to the drawings, A designates a 30 hook for a garment or other purpose, the same being formed of the shank or back member B, the bill C, the fastening-eyes D D E, and the hump or shoulder F, it being noticed that the eyes D D are at one end of the back member B, and the loop or eye E at the other end or front thereof, by which provision the hook may be stitched or sewed in position at both of its ends, whereby it is prevented from rising at the bill end and from shifting, 35 slipping, and overturning, it being also noticed that said eye E projects outwardly from the outer bends G of the bill, so as to be somewhat removed therefrom, whereby when an eye member is applied to the hook and seated against the inner face of said bends (see dotted lines, Fig. 2) it cannot contact with and cut the stitches on said eye, the security of fastening of the hook at the eye E thus being assured. Furthermore, the eye E 45 is located between the side members of the

bill and obviates the employment of laterally-projecting eyes or loops on opposite sides of the back member.

In manufacturing the hook of wire I first 55 may form one of the eyes D and continuing from one side of the back member B the bill C, the loop or eye E, the other side of the back member, the other eye D, and the hump or shoulder F, the latter terminating in a short loop H, which freely embraces the inner end of the loop or eye E, thus preventing said loop from presenting a rough or cut edge to the garment or article to which the hook is secured, it being noticed that said eye E extends rearward of the front bends of the 60 bill into the shank of the hook, so that said loop H may interlock with said eye E at the inner end thereof, as above stated. It will also be noticed that a portion of the loop or eye E is interlocked with the contiguous portion of the back member or shank, as at J, 65 thus stiffening the connection of said eye, with said member close to the adjacent bend of the bill, thus preventing spreading of said parts and accordingly strengthening the hook at the 70 relative places, while said loop is prevented from upward or downward displacement.

75 It is evident that various changes may be made in the details of construction shown without departing from the general spirit of 80 my invention, and I do not, therefore, desire to be limited to the exact construction herein shown and described.

Having thus described my invention, what I 85 claim as new, and desire to secure by Letters Patent, is—

1. In a hook of the character stated, a bill, a back member or shank, attaching-eyes on the ends of the latter, and a front eye projecting longitudinally beyond the outer bends of said bill, the several attaching-eyes being substantially in the same plane, said front eye being continuous of one of said outer bends of the bill and one member of said shank.

2. In a hook of the character stated, a bill, 95 a back member or shank, attaching-eyes on the ends of the latter, and an attaching-eye at said bill projecting longitudinally beyond the outer bends thereof, the several attaching-eyes being substantially in the same plane, 100

the eye at the bill interlocking at one side with an adjacent member of said shank and being continuous at the other side of one of the outer bends of the bill.

5 3. A hook of the character stated having at the bill end thereof a front attaching-eye located between the side members of the bill and interlocking with an adjacent member of

the shank of the hook, a hump member and a loop on the end of the latter, said loop being 10 interlocked with the rear of said front eye.

EMMA V. LAKE.
